COMBINED STEAM AND ELECTRIC
LOCOMOTIVE

Peter H. Ferrier, Brookfield, Ill.

Application September 16, 1936, Serial No. 101,165

3 Claims. (Cl. 105—36)

This invention relates to a combined steam and electric locomotive.

The invention aims to provide, in a manner as hereinafter set forth, a locomotive of the class referred to whereby increased power is obtained from the same amount of fuel employed for a steam generating means forming a part thereof; a greater amount of efficiency is obtained; a greater distribution of power over a longer surface is obtained; pre-heated air is employed for combustion; the use of the forward motion of the locomotive is employed to force a draft into the firebox; the use of a condenser at the front end of the locomotive will add to the power of steam turbine for operating an electrical generator, both forming elements of the locomotive; the locomotive is set up to provide a stream-line effect; the weight is spread over the entire area of the locomotive to give thoroughly efficient traction; the locomotive is formed of three articulated sections to constitute a unit and with each section having an individual drive; the locomotive includes a steam driven propulsion means and a plurality of electrically driven propulsion means; and whereby the exhaust from the steam driven propulsion means is utilized to provide for the operation of a means for generating electricity employed for operating the electrical propulsion means and with the latter operating jointly with the steam driven propulsion means thereby increasing the horse power of the locomotive without increasing the consumption of the fuel employed in connection with the generating of the steam for operating the steam driven propulsion means.

Further objects of the invention are to provide, in a manner as hereinafter set forth, a combined steam and electric locomotive which is comparatively simple in its construction and arrangement, strong, durable, thoroughly efficient in its use, conveniently controlled and readily assembled.

With the foregoing and other objects, which may hereinafter appear, the invention consists of the novel construction, combination and arrangement of parts as will be more specifically referred to and are as illustrated in the accompanying drawings wherein is shown an embodiment of the invention, but it is to be understood that changes, variations and modifications may be resorted to which fall within the scope of the invention as claimed.

In the drawings:

Figures 1 and 1^a, when taken together illustrate diagrammatically a combined steam and electric

locomotive, in accordance with this invention and with the illustration being partly in section, partly broken away and partly in elevation,

Figure 2 is a section on line 2—2, Figure 1,

Figure 3 is a section on line 3—3, Figure 1, 5 and

Figure 4 is a diagrammatical view illustrating the circuit arrangements and controlling means for the electrical driving motors.

The locomotive, in accordance with this invention, is of stream-line contour and includes a front mobile steam propelled combined tender, condenser and air intake element or section 1, an intermediate mobile electrically propelled combined cab and boiler element or section 2, and a 15 rear mobile electrically propelled electrical generating plant carrying element or section 3.

The elements 1, 2 and 3 are articulated together by any suitable means in spaced relation. The space between elements 1, 2 will be closed over 20 by a suitable cover 4. The space between elements 2, 3 will be closed over by a suitable cover 5.

The element 1 has parts thereof forming a water tank 6, and a fuel bin or compartment 7 arranged at the rear of the tank 6. The upper 25 portion of one side of the tank 6 is inset as at 8. The tank 6 extends from the forward end of bin 7 to a suction fan 23 to be referred to. A member 9 is hinged, as at 10, to the body of tank 6 for the purpose of forming in connection with the inset part 8 a passage 11. The front of element 1 is indicated at 14 and it inclines rearwardly from its bottom to its top. The lower end of front 14 constitutes a pilot 15. The upper portion 16 of the front 14 is in the form of a grille. 30 Positioned against the rear of the grille 16 and extending above the latter is a condenser 17 of suitable form which inclines rearwardly from its bottom to its top. Extending through the upper portion of and rearwardly from the condenser 17 35 is the front section 18 of an air intake line 19. The outer end of the top of section 18 is extended forwardly to provide a deflector 20. The forward travel of element 1 forces a draft through the line 19 into the firebox of a steam boiler to 40 be referred to. The front section 18 of the line 19 extends through the passage 11 from end to end of the latter and into cover 4.

The element 1 includes a pair of reciprocating engines 21, only one shown. The engines 21 are 50 of well-known form and are suitably supported in proximity to the front 14. Each engine 21 constitutes an operating means for a set of tandem-wise suitably connected together driving wheels 22 of known arrangement. The element 1 in- 55

cludes the suction fan 23 which is supported in proximity to the condenser 17. The fan 23 is surrounded by an open front housing 23^a formed at its rear, as at 23^b, in a manner to direct the 5 air downwardly. A filling opening for tank 6 is indicated at 24.

The element 1 includes a supporting structure for the tank, bin, fan and housing 23^a. The wheels 22 are carried by axles 25. The said supporting structure is generally indicated at 26 and in which the axles 25 are mounted. Springs 15^a are interposed between the tank 6 and structure 26. Pilot wheels 26^b are provided for section 1. The bottom of the tank is inset, as at 27, to provide clearances for the wheels 22.

The element 2 includes a supporting structure 28 having as parts thereof a pair of trucks 28^a. The element 2 includes a plurality of pairs of supporting wheels 29. Each pair of wheels 29 is mounted on an axle 30 which is supported by a truck 28^a. The element 2 includes two pairs of motor driven traction wheels. The traction wheels of one of said pairs is indicated at 31 and those of the other of said pairs at 32. The 25 wheels 31 are carried by an axle 33 which is connected to one of the trucks 28^a. The wheels 32 are carried by an axle 34 which is connected to the other of the trucks 28^a. The axles 33, 34 have connected thereto electric motors 35, 36 for driving them. The motors are enclosed in motor boxes, such as illustrated at 37, Figure 3. Arranged above the structure 28 is a housing or hollow structure 38 having a bottom 39 and sides 40 depending below said bottom. The structure 28 is pivotally connected to housing 38. A portion of the housing 38 constitutes a cab 41 for the engineer and fireman. Each side of cab 41 is provided with a door 41^a. The floor 42 of the cab 41 is arranged above the bottom 39 of housing 38 thereby providing a chamber 43. The bottom 39 of housing 38 has an inset portion 44. The structure 28 includes springs 45 which bear on the trucks 28^a. The inset portion 44 provides clearances for the wheels of element 2.

45 Arranged within the cab 41 is a cutout of known construction positioned in a box 46. The cutout is employed in connection with a power circuit 47 leading from an electrical generating apparatus to be referred to. Interposed in the circuit 47 is a controller of known form positioned in a box 48 arranged in the cab 41. The power circuit 47 leads to a controlling mechanism 49 positioned in the cab 41. The mechanism is employed for selectively controlling the operation of the electrical driving motors 35, 36, and the motors 50 and 51 to be referred to. The operating circuits for the motors 35, 36, 50 and 51 are indicated at 52, 53, 54 and 55 respectively. The controlling mechanism 49 is not only employed to cause the independent operation of the driving motors, but is also employed to cause the operation of the said driving motors in unison. The controlling mechanism 49 is arranged in the cab 41.

60 The element 2 includes a steam boiler 52^a, a firebox 53^a and an ash pit 54^a. The boiler 52^a is provided with a steam dome 55^a. The ash pit 54^a will be closed at its sides and bottom so as to not interfere with forced draft through the line 19. The ash pit will be accessible through a door 87^b (Figure 1) at its front.

65 The element 3 includes a housing or hollow structure 56 having its bottom arranged above the lower ends of its sides. The housing 56 is supported in a manner similar to the manner in 70 which the structure 38 is supported, that is to say,

75 by a structure similar to structure 28 provided with a pair of trucks 57^a. The element 3 includes a pair of supporting wheels 59 carried by an axle 60, a pair of electrically driven traction wheels 61 carried by an axle 62, a pair of electrically driven traction wheels 63 carried by an axle 64 and a pair of supporting wheels 65 carried by an axle 66. Connected to the axles 62 and 64 are the electrical driving motors 50, 51, respectively therefor. The axles 60, 62 are mounted in one of the trucks 57^a, and the axles 64, 66 are mounted in the other of the trucks 57^a. The motors 50, 51 are enclosed in motor boxes in the manner as shown in connection with the axle 33 as indicated at 37, Figure 2.

80 The locomotive includes a sectional steam supply line 72 which extends from the dome 55^a through the cover 4 into and out of passage 11 and communicates with the engines 21 for the purpose of supplying steam to these latter. Communicating with the engines 21, extending rearwardly therefrom, into and out of passage 11, through cover 5, into the element 3 and opening into the turbine 68 is a sectional conducting line 73 for conducting exhaust steam from the engines 21 for the purpose of utilizing the exhaust steam to drive the turbine 68. The line 72 is provided with a controlling valve 74 operated from within the cab 41. Leading from the turbine 68, extending through the cover 5, through the element 2 and into the element 1 and opening into the upper portion of the condenser 17 is a line 75 for conducting exhaust steam from the turbine 68 to the condenser 17. Leading rearwardly from the dome 55^a through the cover 5 and into the element 3 and opening into the rear end of 73 is a sectional steam conducting line 76. The line 76 has interposed therein a controlling valve 77 actuated by the means 78 which extends into the cab 41 and is operated from within the latter. 85 The pipe 73 has interposed therein a pair of spaced valves 73^a, 73^b and a relief valve 73^c set for fifteen pounds of pressure. The valves 73^a, 73^b and 73^c have connected thereto actuating means 73^d therefor operated from within the cab 41. Leading from the housing of valve 73^a and opening into a smoke flue 91 is by-pass or steam exhaust conducting branch 73^e. Leading from the lower portion of the condenser 17 and extending through element 1 and opening into the bottom of a hot well 79 is a condensate conducting line 80. The well 79 is arranged in element 2. The front section 18 of line 19 is coupled within cover 4 to the rear section 82 of line 19. The rear section 82 is arranged within element 2 below 90 the floor 42. The section 82 of line 19 includes an upper portion 83 of inverted L-shaped contour and a horizontally disposed lower portion 84 which is open at each end. The portion 83 opens into the portion 84 intermediate the ends thereof. The portion 84 opens into the ash pit. Arranged within the forward part of the portion 84 is a suction fan 85 operated and controlled by any suitable means. The latter is positioned forwardly of the point of communication between 95 portions 83 and 84. The forward open end of the portion 84 is controlled by a normally closed hinged valve 86, which is shifted to open position by the means 87 for the purpose of supplying air when the locomotive is not in motion. The means 87 extends up through floor 42 and is operated from within the cab 41. Extending within the portion 84 of section 82 is a shiftable damper 87^a for the rear end of said portion 84 and which is operated by the door 87^b of the firebox. The 100

damper 87^a is so connected with the door 87^b to provide for the damper being closed when the door is open and opened when the door is closed. The line 19 is provided for creating a draft of preheated air when the locomotive is in motion for entrance into the firebox through the grates for the purpose of increasing combustion. The air entering line 19 is heated as it passes through the condenser 17 and conducted for discharge 10 into the ash pit for passage therefrom into the firebox. Leading from the water tank 6, extending through the cover 4 into the element 2 and opening into one side of the hot well 79 is a sectional water supply line 88. Arranged within the 15 element 2 is a water feed line 89 which extends from the other side of the hot well 79 and opens into the water space of the boiler 52^a. The line 89 has interposed therein a feed water pump 90. The element 2 is provided with a smoke discharge 20 flue 91 leading from the firebox of the boiler.

Interposed in the line 75 is an oil separator 92.

The line 76 is for supplying steam to the turbine at full boiler pressure when the locomotive is running slow and under a heavy load. The 25 valves 73^a, 73^b of line 73 and the relief valve 73^c are to be employed when the turbine is using steam at boiler pressure. The purpose of valve 73^a and by-pass 73^b is to allow the exhaust steam from the engines to escape when the turbine is 30 working under high pressure. The valve 73^b keeps the high pressure steam from escaping before entering the turbine. The relief valve 73^c keeps the back pressure on the reciprocating engines from increasing when working with the turbine.

There may be obtained, from within the cab, a clear view of the track on both sides by the engineer or fireman.

The condenser is located at the front of the 40 train as this is the coolest and most exposed place for obvious reasons and is inclined to prevent air resistance. The turbine and electric generators are not placed here as there are no independent drive wheels for the forward section. 45 The water tank, boiler and coal are of course located near together, and the forward motion of the train adds to the draft in the firebox. The

engineer and fireman are located in the front of the second section as the extreme front might be the point of greatest danger, but this position brings the fireman adjacent the firebox and coal supply, and also gives a forward unobstructed 5 view. The air inlet located above the condenser is at the hottest point of the latter and feeds to the firebox.

What I claim is:—

1. A streamlined locomotive including steam 10 generating means and a driving engine, connecting means to conduct the steam exhausted from said engine to a secondary steam engine, connections for the exhaust therefrom to a condenser, said condenser forming a portion of the front 15 of the locomotive and being upstanding and rearwardly inclined, an air intake line extending through the upper portion of the condenser, an air deflector overhanging said intake line and adapted to pick up air deflected upwardly from 20 the condenser of the locomotive.

2. A streamlined locomotive having an air deflecting pilot, a grille thereabove and a condenser immediately back of the grille and at the front of the locomotive and forming a continuous surface 25 for deflecting air upwardly, said pilot, grille and condenser being upstanding and rearwardly inclined and forming the front of the locomotive, means to conduct exhaust steam to the condenser, an air intake line extending through the upper 30 portion of the condenser, an air deflector projecting forwardly from the top of the intake line and adapted to direct air deflected upwardly by said pilot and condenser into said line.

3. In a locomotive including steam cylinders 35 and their connections and driving wheels, a pilot in front thereof and a grille above said pilot, forming an extension thereof and both inclined rearwardly from the bottom to the top at an upwardly slanting angle, a condenser inclined immediately back of said grille and extending from immediately above the pilot to the top of the locomotive, an air inlet pipe extending through the top of the condenser and its upper portion extending forwardly to form means for deflecting 45 air into said pipe.

PETER H. FERRIER.
